DERRICK CONSTRUCTION

Leslie A. Rawson, Los Angeles, Calif.

Application September 21, 1938, Serial No. 230,977

10 Claims. (CL. 189—16)

This invention relates generally to derrick constructions of the type used in conjunction with oil or gas wells.

It is a general object of the invention to afford a derrick of simple design, which can be erected without undue expense, and which will afford a greatly increased amount of operating room within the derrick for the racking of pipe.

It is a further object of the invention to afford a derrick as described above, without materially departing from the stress distribution encountered in derricks of conventional design.

Additional objects of the invention will appear from the following description in which the preferred embodiment of the invention has been set forth in detail in conjunction with the accompanying drawing.

Referring to the drawing:

Fig. 1 is a side elevational view, illustrating a derrick incorporating the present construction.

Fig. 2 is a cross-sectional view taken along the line 2—2 of Fig. 1.

Fig. 3 is an enlarged detail in perspective, illustrating the manner in which the cross bracing on at least one side of the derrick is offset laterally, and attached to the remainder of the structure.

The present invention can be applied to a variety of derricks wherever it becomes desirable and necessary to afford an increased amount of operating space within the structure. The drawing, however, illustrates a steel derrick of the combination type, and the increased amount of operating space in this instance has been afforded upon what is commonly referred to as the ladder side.

To describe the structure as illustrated in the drawing, it consists of four upright structural members 10, 11, 12 and 13, which assume substantially all of the vertical stress components of the derrick, and which can be in the form of angles or like structural steel shapes. In conformance with customary practice these vertical members are connected together by sets of connecting members comprising the horizontal girts 14 and 15, and cross bracing 16 disposed on three sides of the derrick, such sets being customarily referred to as bays.

In a conventional derrick the disposition of the girts and cross bracing is the same for all four sides of the derrick. However, with such a design there is a limited amount of operating room within the derrick which is available for the racking of pipe.

According to the present invention in place of

applying the girts and the cross-bracing in the customary manner, these members are displaced laterally on at least one side of the derrick, in this instance the right hand side as viewed in Figs. 1 and 2. Thus a number of the girts 14 on opposite sides of the derrick are made of increased length to afford the extensions 14a. The girts 15a which in a conventional construction would extend directly between upright members 10 and 12, are now attached to the ends of extensions 14a so as to provide a window or opening through the derrick side. The cross-bracing 16a is also displaced to the general plane of the girts 15a, and as an added reinforcement the ends of the extensions 14a are connected by vertical members 17 thus forming a chamber outside of the normal confines of the derrick for receiving the upper ends of pipe racked within the derrick.

Fig. 3 illustrates a suitable detail for making the connections as described above. Auxiliary generally vertical members 17 are shown attached to the ends of extensions 14a, while the ends of the cross-bracing 16a connect with the points of intersection of the girts 15a and member 17.

The amount of added room afforded within the derrick depends upon the length of the extensions 14a. In general it is feasible to increase the room for racking pipe by from 25% to 50%, without the necessity of increasing the strength of the girts 14. Generally it is desirable that the increased operating space be afforded for a distance extending somewhat above the operating platform 18. At this point the offset may terminate abruptly, or it may taper back into the outline of the derrick, as illustrated in Fig. 1.

Fig. 2 illustrates diagrammatically a racking finger board 19, used in the racking of pipe. The center of the well hole is at 20, which also is coincident with the center line of the derrick about which the upright structural members 10, 11, 12 and 13 are symmetrically disposed. The space to the right of the finger board 19 is available for racking pipe. With a conventional derrick this space will be limited to the distance between the finger board and the plane of the structural members 10 and 13. However, with the present invention this space is now extended to the plane of the girts 15a and the cross-bracing 16a.

One feature of my invention is that the distribution of stresses in the various structural members and bracing remains substantially the same as for a conventional derrick not provided with the offset. In other words the transposing of the girts 15a and cross-bracing 16a to the

ends of the girt extensions 14a, does not weaken the structure or alter the distribution of stresses to any material degree. The only change insofar as distribution of stresses is concerned is that the stresses applied to girts 15a and 16a are transmitted first through the girt extensions 14a. For reasons just explained all of the vertical stress components which would otherwise be received by the vertical structural members 10, 11, 10 12 and 13, are still transmitted and received by these members, without material change in magnitude or direction. Therefore the utilization of the present invention in the building of a derrick does not involve undue expense, and does 15 not increase the cost to any marked degree.

It will be evident that, if desired, girt extensions may be provided upon two opposite sides of the derrick, and the girts and cross-bracing upon both sides attached to the girt extensions. However, for the majority of operating conditions it 20 is deemed that added room afforded on one side of the derrick, will suffice.

I claim:

1. In a derrick construction for oil and gas wells, four upright structural members symmetrically disposed about a vertical central axis, said members serving to carry substantially all of the downward force components of the derrick in compression, auxiliary generally vertical structural members on one side of said derrick spaced laterally from a pair of said upright structural members for a substantial portion of the height of the derrick, means connecting said auxiliary structural members with said pair of upright structural members, and cross-bracing connecting said auxiliary structural members to provide cross-bracing offset laterally from said pair of upright structural members, there being no cross-bracing between said pair of upright structural 30 members through substantially the height occupied by said auxiliary structural members, whereby added working space is afforded within the derrick between said pair of upright structural members.

2. In a derrick construction for oil or gas wells, four upright structural members symmetrically disposed about a vertical central axis, said members serving to carry substantially all of the downward force components of the derrick in compression, cross-bracing serving to connect said members to form a rigid structure, and means arranged and constructed so that the cross-bracing on at least one side of the derrick is offset laterally from a pair of said upright structural members over a substantial portion of the height of the derrick, to afford additional space within the derrick for racking pipe.

3. In a derrick construction for oil or gas wells, four upright structural members symmetrically disposed about a vertical central axis and carrying substantially all of the downwardly directed force components of the derrick in compression, and cross-bracing serving to connect said members to form a rigid structure, said cross-bracing including girts extending laterally beyond a pair of said upright structural members on at least one side of said derrick for a substantial part of its height, the cross-bracing on said side being connected with said pair of structural members by said extended girts, whereby the cross-bracing on said side is offset laterally relatively to said pair of structural members to afford added space within the derrick for racking pipe.

4. In a derrick construction for oil or gas wells, four upright structural members disposed sym-

metrically about a vertical central axis, and assuming substantially all of the downward force components of the derrick in compression, a plurality of horizontal girts attached to said structural members at two opposite sides of the derrick, certain of said girts having extensions beyond the adjacent structural members at a third side of the derrick, cross-bracing connecting certain of said structural members to strengthen the derrick, the cross-bracing on said third side 10 of the derrick being attached to the ends of said girt extensions, to afford added space within the derrick for racking pipe.

5. In a derrick construction for oil or gas wells, four upright structural members symmetrically disposed about a vertical central axis, said members assuming substantially all of the downward force components of the derrick, a plurality of horizontal girts directly connected to and extending between said members on three sides of the 20 derrick, the girts on two sides of the derrick being extended on the fourth side of the derrick beyond the line of the adjacent structural members defining said fourth side, cross-bracing on said three sides of the derrick, said cross-bracing 25 being substantially in planes coincident with the line of centers of adjacent structural members, and cross-bracing on said fourth side of the derrick beyond said line of said adjacent structural members and between the ends of said extended 30 girts, whereby added working space is afforded within the derrick.

6. In a derrick construction for oil or gas wells, four upright structural members adapted to assume substantially all of the downward force components of the derrick in compression, a plurality of girts attached to said structural members and extending between said structural members on three sides of the derrick, certain of said girts having extensions on the fourth side of the 40 derrick, auxiliary generally vertical structural members connecting the ends of the girt extensions, cross-bracing on said three sides of the derrick, said cross-bracing being disposed in planes substantially coincident with the line of 45 centers of adjacent upright structural members, and cross-bracing upon the fourth side of the derrick extending between said auxiliary structural members whereby added working space is afforded within the derrick for racking of pipe, 50 and whereby said cross-bracing upon the fourth side of the derrick strengthens the derrick substantially the same as if said cross-bracing were directly applied to the adjacent upright structural members.

7. In a derrick of the type described, the combination of: a base; and a derrick structure extending upward from said base, said derrick structure having corner members secured together by sets of connecting members lying in the planes 60 defined by adjacent corner members, one of said sets of connecting members being spaced outwardly from the plane of the corner members which it connects so as to form an external chamber lying outside said plane to receive the upper end 65 of a pipe standing on the base of the derrick.

8. In a derrick of the character described, the combination of: corner members extending in upright and spaced relation so as to define a derrick space; sets of connecting members arranged 70 in consecutive order and connecting adjacent corner members together; and means to space at least one of said sets of connecting members outwardly from the plane defined by two adjacent corner members, so as to provide a space lying 75

exterior of the derrick and in communication with the interior base of the derrick, to receive the upper end of a pipe standing on a floor at the lower end of the derrick.

9. In a derrick of the character described, the combination of: a base; and a derrick structure on said base comprising a plurality of bays arranged in vertical order, at least one of said bays in the upper portion of the derrick structure being laterally enlarged at a side thereof so as to form a chamber which communicates with the interior of the derrick and projects laterally therefrom so as to provide a space lying outside the

derrick proper to receive the upper end of a pipe standing on the base of the derrick.

10. In a derrick of the type described, the combination of: a base; and a derrick structure extending upward from said base, said derrick structure being formed of a structural part defining side planes for the derrick, there being structural parts secured to the upper part of the derrick so as to lie outside one of said side planes and form a pipe-head chamber communicating with the interior of the derrick structure. 5
